UNITED STATES PATENT OFFICE.

MONTEFIORE L. HIRSCH AND GEORGE W. BLACKSTOCK, OF BALTIMORE, MARYLAND,
ASSIGNORS, BY MESNE ASSIGNMENTS, TO SAID HIRSCH.

PAPER-BAG MACHINE.

1,053,947.

Specification of Letters Patent. Patented Feb. 18, 1913.

Application filed February 21, 1912. Serial No. 678,984.

To all whom it may concern:

Be it known that we, MONTEFIORE L. HIRSCH and GEORGE W. BLACKSTOCK, citizens of the United States, residing at Baltimore, in the 5 State of Maryland, have invented new and useful Improvements in Paper-Bag Machines, of which the following is a specification.

Our invention pertains to paper bag machines; and it has for its object to provide 10 a highly efficient machine designed more particularly for manufacturing in a finished manner paper bags of what may be said to be a self-standing square type, this 15 because the bags when opened will have square bottoms and will be capable of standing in upright position, of themselves, before and during the filling thereof.

Many features of our invention will be 20 found well adapted for use in machines for making paper bags of types different from that mentioned, and it will be understood that it is our intention to protect herein the 25 said features irrespective of the kind of paper bag machine in which they are em-

The invention in all of its details will be 30 fully understood from the following description and claims when the same are read 35 in connection with the drawings, accompanying and forming part of this specification, in which:

Figure 1 is an elevation of one side of the machine constituting the best practical embodiment of our invention that we have as yet devised. Fig. 2 is an enlarged view of part of the opposite side of the machine. Fig. 3 is a diagrammatical view showing certain parts of the machine. Fig. 4 is an 40 enlarged front elevation of the machine with the upper pair of blades and the lower pair of blades at the left of the cylinder omitted; it being understood that the said upper and lower pairs of blades at the left 45 are similar to the upper and lower pairs of blades at the right. Fig. 5 is a view, partly in section and partly in elevation, of the rear end of the machine; the web roll being shown in diametrical section. Fig. 6 is a 50 detail section on the line 6-6 of Fig. 5. Figs. 7 and 8 are enlarged detail sections hereinafter specifically referred to. Fig. 8^a is a detail view taken at a right angle to Fig. 5, and showing the friction bearing for

shaft 1. Fig. 9 is an enlarged detail perspective showing the manner in which certain elements of the machine operate on a bag length. Figs. 10 and 11 are enlarged details hereinafter set forth. Figs. 12 and 13 are detail views of the means for forming the continuous web or strip of paper into a tube having side bellows or inward tucks. Fig. 14 is an enlarged detail perspective of the rotary device for forming the thumb hold recesses or openings in the tube at intervals in the length thereof. Figs. 15 and 16 are details of the printing means comprised in the machine. Fig. 17 is a vertical section showing the cylinder and certain parts carried thereby at the left-hand side thereof, looking forward; it being understood that the cylinder is correspondingly equipped at its opposite or right-hand side. Figs. 18 to 22, inclusive, are detail views illustrative of the means for actuating the bag grippers carried by the cylinder; Figs. 18 and 19 showing the cams and the arms coöperating with the cams, located adjacent the right-hand side of the machine looking forward, and Fig. 21 showing the 80 cam and arms coöperating therewith, located adjacent the left-hand side of the machine. In other words, the view point from which Fig. 21 is taken is at the right hand or gear side of the machine, while the view point at which Figs. 18 and 19 are taken is at the left-hand side of the machine—i. e., the side opposite the gear side. Fig. 23 is a plan showing the combined paste-applying and tucking roll which constitutes an important feature of our invention. Fig. 24 is a detail perspective of part of the belt-shifting means comprised in the machine. Fig. 25 is a longitudinal vertical section of so much of a paper bag machine as is necessary to show a modification of our invention; some of the parts of said view being in elevation. Fig. 26^a is a detail of a driving connection in the modification. Figs. 26 and 27 are front elevations of the modification. Fig. 28 is a view showing certain details of the superposed cylinders of the modification. Fig. 29 is another detail of the upper of said cylinders. Fig. 30 is a detail of a cam that coöperates with parts on the lower of said cylinders. Fig. 31 is a view showing the inner side of one of the stationary cams that coöperate with other

parts on the lower of said cylinders. Fig. 32 is a detail view showing one of the tuckers and the pair of bag-engaging blades on the lower of the cylinders. Figs. 33 and 34 are detail views showing the co-operation of the said superposed cylinders. Figs. 35, 36 and 37, are detail views of the upper of said superposed cylinders. Fig. 38 is a detail of the upper of the superposed cylinders showing one of the means thereon for carrying a bag length around with the cylinder.

Similar numerals designate corresponding parts in Figs. 1 to 24 of the drawings, to which reference will first be made.

The main frame of the machine may be of any construction and design consonant with the purpose of our invention.

At the rear end of the main frame is arranged a transverse shaft 1 on which is mounted a roll of paper 2; a continuous strip of paper being drawn from the said roll during the operation of the machine, and the roll 2 and shaft 1 being rotated in consequence. At one end the roll 2 bears against a suitable abutment on the shaft 1, the said abutment being preferably in the form of a plug 3 that is feathered on and adjustable endwise of the shaft and is backed by an adjusting wheel 4, threaded on the shaft.

At 5 the shaft 1 has fixed thereon a friction drum which bears partly in a fixed block 6 and partly in a movable block 7, backed by a screw 8. By turning the screw 8 outward to permit of movement of the block 7 away from the block 6, the friction on the drum 5 and the retardation of the roll 2 is lessened as the roll is diminished in diameter and the leverage exerted by the pull of the paper off the roll is decreased. In this way the paper strip or web drawn off the roll may always be kept under proper tension to assure perfect working of the machine.

The paper roll 2 is tightly held against the abutment 3 and thereby fixed with respect to the shaft 1 by a plug 9, adjustable lengthwise on the shaft. This plug 9 is kerfed at 10, and in the said kerf is pivoted a pawl 11 which serves by engaging teeth 11^a of the shaft 1 to hold the plug against outward movement. Obviously in positioning the plug 9, it is simply necessary for the operator to move the same inward to the extent desired and seat the pawl 11 in one of the interdental spaces of the shaft when the plug will be strongly and safely held against outward movement.

For the purpose of adjusting the shaft 1 and the paper roll 2 lengthwise and adjustably fixing the roll in proper alignment with the bag-forming elements hereinafter described, we provide a notched and laterally movable bearing 12 in which the circumferentially-grooved portion 13 of shaft 1 is

seated, and we also provide an adjusting screw 14 that is threaded in the adjacent portion of the main frame and is journaled and held against endwise movement in the bearing 12. Obviously by turning the screw 14 in one direction, the shaft 1 and roll 2 will be moved as a unit toward the right and by turning the screw in the other direction the shaft and roll will be similarly moved toward the left.

From the roll 2 the strip or web of paper is passed upward in front of and over an idler roll 15, and is then passed back of and over and forward from a second idler roll 16. Located in a horizontal plane below that of the roll 16 is a cross-rod 17, and resting removably on said cross-rod are the bifurcated supports 18 of a paste receptacle 19. Mounted in the paste receptacle and projecting therefrom is a rotary disk 20 the periphery of which is held by the gravitation of the receptacle 19 against the paper as the same passes the roll 16; the said receptacle being adapted to swing forward on the rod. The disk 20 is provided at intervals in its periphery with notches 21, and it moves through the bifurcation 22 of a plate 23 that is fixed to the front wall of the receptacle 19, this in order to enable the plate to remove excess paste from the disk. The disk 20 has for its function to apply paste to the strip or web of paper adjacent one edge thereof with a view of contributing to the formation of the web into a tube as hereinafter described. The notches 21 in the disk serve the important purpose of mincing any paste lumps that may be taken up by the disk, and in that way assure the proper initial application of paste to the web of paper.

After passing over the roll 16 the web of paper is formed into a tucked tube—i. e., a tube having inwardly extending side folds, by simple and reliable means which will now be described; the said means serving the purpose stated while the web is being swiftly drawn forward so as not to detract from the capacity of the machine. The said means comprises a lower longitudinal-central plate 25 which is connected through a hanger 26 with a transverse frame bar 27 and has an upturned rear end 28, an upper longitudinal-central plate 29 spaced from the plate 25, tucking plates 30 extending from opposite sides into the space between the plates 25 and 29, upright spaced bars 28^a rising from the plates 30 and having convex opposed sides, a blade 31 that extends forward and inward from the right-hand side of the path of the paper and immediately over the paper thickness to which the paste-bearing edge is connected, and pressing wheels 32 each of which bears on one of the upper thicknesses of the tube. After the web of paper passes over the roll 16 it is

drawn forward in channeled form, with the bottom of the channel under the plate 25, and the side walls of the channel at opposite sides of the hanger 26 and between the upper rights 28^a and also between the tucking plates 30, after which one of the upper thicknesses passes under the blade 31 and both upper thicknesses pass under the pressing wheels 32, after which the tube is carried between driven drawing rolls 33 and 34. In this way the continuous tucked tube is expeditiously and properly formed incidental to the swift forward movement of the web of paper; the wheels 32, forwardly converged, crowding the paper inward on the forming plates.

For the purpose of forming openings in the lower thickness or wall of the tube, (which opening will form thumb-holes at the mouths of the bags when the same are cut from the tube), we provide the driven rotary device 35 which works through an opening 35^a in the plate 25, Fig. 13. This device comprises a suitable body, toothed cutting blades 36, arranged in a curved manner, and resilient fingers 37 which have for their function to press the paper away from the toothed blades 36—*i. e.*, to prevent the paper adhering to said blades and interfering with the smooth and continuous operation of the machine.

In order to print any desired inscription upon the lower side of the tube at points adjacent the curved cuts or recesses in the lower thickness of the tube, we prefer to provide the upper draw roll with an elastic bed 39, and the lower draw roll 34 with a type form 40, and we also prefer to supply an adequate quantity of ink to the said form 40 through the medium of an inking roll 41, which roll 41 is supplied with ink by a fountain roll 42. These elements are best shown in Figs. 15 and 16, and will be hereinafter specifically described.

45. After passing between the draw rolls 33 and 34, the tucked tube passes between retarding rolls 43 and 44, which retarding rolls are driven. These rolls 43 and 44 are termed retarding rolls because they bring about a slackening or slight buckling of the paper tube between themselves and the cutting-off means, and in that way contribute materially to the sure production of neat and finished cuts at the mouth end of the bags. The rolls 43 and 44 bring about the said slackening or buckling of the paper tube as stated by reason of the roll 43 being provided with a blade 45 and the roll 44 being provided with a kerf 46 complementary to the blade and into which a portion of the tube is pressed by a blade. When the said pressed or deflected portion of the tube is released from and moves forward of the rolls 43 and 44, it creates the mentioned slack or buckling of the tube.

This latter will be appreciated as an important advantage when it is stated that experience has demonstrated that the bags cannot be cut in a neat and finished manner from the tube when the tube is taut or under tension.

70 The plates 25 and 29 have their forward ends converged and extended to a point immediately in rear of the meeting portions of the draw rolls 33 and 34 so as to assure the proper passage of the tube between said rolls.

In passing to and forward from the rolls 43 and 44 the paper tube moves on side by side plates 47 which have a space between their inner edges to permit the described operation of the retarding rolls, and said plates 47 also extend forward to points above the cylinder 48, which constitutes one of the most important features of our invention, 80 and back of the vertical center of the cylinder. Located above the vertical center of the cylinder 48 and supported in the main frame of the machine is a roll 49. The said roll 49 is equipped with a tucking blade 50, 90 and is also equipped with two blades 51, having toothed edges 52; the said blades being carried by levers 53 that are fulcrumed at 54 and are returned to and held in their normal idle positions by coiled springs 55. 95

At their outer ends the levers 53 are provided with anti-friction rollers 56, and these latter at the proper point in the revolution of the roll 49 wipe past tappets 60 which are preferably, though not necessarily, carried by brackets 61 that are adjustably connected to the main frame. By virtue of this it will be manifest that when the anti-friction rollers 56 wipe or pass over the tappets 60, the blade-bearing arms of the levers 53 will be sharply moved toward the center of the cylinder 48, and in consequence 100

a bag length will be cut in a shearing manner from the paper tube. This cutting of the bag length in a shearing manner constitutes an important feature of our invention since it assures the production of a finished cut which in no way will detract from the appearance of the mouth ends of the completed bags. After the anti-friction 110

rolls 56 are clear of the tappets 60, the springs 55 promptly return the levers and the blades to their normal positions and thereby preclude the possibility of the blades interfering with the smooth and continuous 115 operation of the machine. At this point we would say that while we prefer to return the levers and the blades to the idle positions through the medium of springs 55, we do not desire to be understood as confining 120 ourselves to springs for the specific purpose stated, inasmuch as other means may be provided without involving departure from the scope of our invention as claimed.

125 The tucking blade 50 and the shearing 130

blades 51 are relatively arranged, as shown in Fig. 17, for a purpose hereinafter set forth.

The cylinder 48 in the present embodiment of our invention is provided with six groups of features or organized mechanisms for handling bag lengths, but we would here have it understood that the cylinder may be provided with any number of such 10 groups of features or organized mechanisms without involving departure from the spirit of our claimed invention.

Formed in the periphery of the cylinder 48 and extending continuously around the 15 same is a central groove 62, and at equidistant points or places in the periphery of the cylinder are formed or provided six groups of features such as shown in the middle of Fig. 4. These groups of features 20 are identical, and therefore a detailed description of the group in the figure just mentioned and the elements that coöperate therewith, will suffice to impart a definite understanding of all. The group of features 25 to which reference is made comprises a recess 63 in communication with the aforesaid groove 62, and also in communication with a transverse groove 64. The timing of the parts is such that the groove 64 of 30 each group of features will receive the shearing blades 51 on the roll 49, and the groove 65 of each group of features will receive the tucking blade 50 on said roll 49 during the operation of the machine. The 35 groove 64 is arranged in front of the groove 65 with reference to the direction in which the cylinder 48 rotates, and between the groove 64 and the groove 65 is a groove 66. Back of the groove 65 is a groove 67. In 40 the groove 66 is what will hereinafter be denominated the first gripper 68, which grips backward, and in the groove 65 is the second gripper 69, which grips forward, while in the groove 67 is the third or rear 45 gripper 70, which also grips forward. The backward gripping of the first gripper and the forward gripping of the third or rear gripper is an important feature since it precludes tearing of the bag length, and in 50 that way contributes to the reliability of the machine. Each of the grippers 68, 69 and 70 is provided with a central notch 71 which registers with the groove 62 so as not to interrupt the continuity of the latter. 55 Each of the mentioned groups of features comprises pairs of lateral rods 72 at opposite sides of the series of transverse groups of grippers, two carriages 73 movable laterally on said rods at opposite sides of the cylinder 48, and blades 74 and 75 carried by the said carriages, there being one blade 74 and one blade 75 to each carriage. The carriages are similar in construction, and the blades 74 and 75 of one carriage are 60 similar to the blades 74 and 75 of the car- 65

riage at the opposite side of the cylinder 48. Therefore a detailed description of the carriage and the blades 74 and 75 will suffice to impart a definite understanding not only of said carriage and blades, but of the complementary carriage and blades at the opposite side of the cylinder 48. The blade 74 is carried by a lever 76 fulcrumed at 77 to swing away from and toward the center of movement of the cylinder, and provided 70 with an inwardly extending rod 78, Fig. 11. The rod 78 serves to move the lever 76 and the blade 74 outward when said rod is actuated by a cam hereinafter described, and the lever and the blade are strongly though 75 yieldingly moved inward by a spring 79, Fig. 11, which directly engages the rod 78. The blade 74 is arranged in front of the blade 75, with reference to the direction of rotation of cylinder 48, and said blade 75 is carried by a rock-shaft 80 having a pinion 81 on its outer end intermeshed with a gear sector 82, which gear sector forms one arm of a lever, the other arm of which is equipped with a lateral projection 83 movable by a cam hereinafter described. The purpose of the said mechanism is to swing the blade 75 from a superposed position on the blade 74 backward to the position shown 80 in Fig. 9, and when the lateral projection 83 is so disposed relative to the mentioned cam as to permit, the blade 75 is swung back to a superposed position on the blade 74, the latter movement being accomplished by a torsion spring 84 which surrounds the 85 shaft 80 and is connected at one end thereto and at its opposite end to the carriage 73. It will be understood here that the said spring 84 is put under tension by the described positive movement of the blade 75 90 95 100 105 110 115 120 125 130

backward, and hence when forward swinging movement of the blade 75 is permitted, the spring expands and in that way accomplishes said movement of said blade 75. Disposed in front of the cylinder 48 are stationary, curvilinear retaining rods 85, and disposed in front of the roll 49 that carries the tucking blade 50 and the shearing blades 51, is a stationary back 86. Movable forward and rearward in front of the back 86 is an oscillatory ironer or smoother 87, which is preferably shaped as shown. Mounted in front of the said ironer or smoother 87 is a shaft 88 on which is fixed a circumferentially grooved pulley 89, equipped with opening arms 90. Around the said pulley 89 passes a band 91 which also passes around a grooved roll 92 that is smaller in diameter than the pulley 89, and is arranged nearer the perimeter of the cylinder 48 than the said pulley 89. At this point it is well to state that the pulley 89 is driven faster than the cylinder 48 for a purpose hereinafter set forth.

It will be remembered that the purpose of 130

he rotary device 35 is to make cuts in the lower thickness or wall of the tube, and we would here explain that the purpose of the recess 63 of the group of features described 5 is to prevent the severing blades 51 from detaching or severing from the lower wall of the tube the tongue 93 left on the said lower wall by the said rotary device 35, which tongue 93 is clearly shown in Fig. 9.

10 For convenience of description and before describing the means for actuating the grippers 68, 69 and 70, and the blades 74 and 75 of each group of features appurtenant to the cylinder 48, we will describe in detail 15 how each group of features operates on a bag length in combination with the smoother or ironer 87, the back 86, the arms 90 and the band 91. In the first place, while the blades 75 are superposed on the blades 74, 20 and the said blades are approaching the point above the vertical center of the cylinder 48, the said superposed blades are slightly raised to carry them beyond the periphery of the cylinder. Then during the 25 time of the action of the middle gripper 69, the blades 74 and 75 in superposed relation are further slightly moved or raised beyond the periphery of the cylinder and then are fully advanced into the side tucks or bellows 30 of the bag. Then immediately after the action of the gripper 69 the blades 74 clamp the lower parts of the bellows of the bag against the periphery of the cylinder. Immediately following this, the blades 75 are 35 swung backward from their position on the blades 74 to lay back the top portions of the bellows, and in this way the bottom of the bag is opened. Then the ironer or smoother 87 serves the two-fold function of completing 40 the opening of the bottom, that is it smooths the top or rear portion of the bottom, and then withdraws or moves forward to a point where it engages and retards the rear portion of the bottom precedent to the 45 closing of the bottom. Prior to the said retarding action of the said iron or smoother 87, the revolving arms 90, operating faster than the cylinder 48, lay down the tongue 93 and the portion of the bag carrying the same, 50 so as to assure the uninterrupted movement forward of the said tongue and portion with the cylinder 48 and under the retainers 85, and also under the stretch of the belt that is opposed to the periphery of the cylinder 48. 55 Just prior to the taking hold of the incomplete bag bottom by the forward gripper 68, the blades 74 are withdrawn outward from the bellows or tucks in the sides of the bag length. After withdrawal of said blades, 60 the rear gripper 70 having operated or gripped the bag, the blades 75 (which were withdrawn with the blades 74) are swung forward by the springs 84 to the first-named positions on the blades 74. At this 65 time the bag bottom is held by the forward

gripper 68, the middle gripper 69 and the rear gripper 70. Then the rear gripper 70 releasing the bottom, and paste having been applied by means hereinafter described, to the inner sides of the front wall and rear 70 wall and major portion, adjacent the forward end of the bag, the sweeps, herein-after described, lay down the rear wall of said forward open end. The said forward bag end then enters the finishing rolls, 75 hereinafter described, by reason of which the bottom is completed, and just before this time the front gripper 68 and the middle gripper 69, in the order named, release the bottom. The paste is applied to the 80 bottom being formed between the taking hold of the bottom by the front gripper 68 and the taking hold of the bottom by the rear gripper 70.

85 Suitably supported in front of the cylinder 48 is a paste receptacle 97, and carried by said paste receptacle is a roller 98 by which paste is transferred from the interior of the receptacle to a roller 99 which latter applies the paste to the bottom portions of 90 the bag lengths in the manner before described, as the said bag lengths pass the roller 99. The roller 99 is provided with blades 99^a to tuck the bag length into the cylinder groove 66, and is also provided 95 with a blade 99^b to tuck the bag length into the cylinder groove 67. Hence said roller 99 serves the two-fold function of pasting and tucking, which is an important advantage. The paste-transferring roller 98 is, 100 of course, provided with grooves complementary to and adapted to receive the blades of the roller 99, one of said grooves being shown in Fig. 17. Supported above the rollers 98 and 99 are guards 99^c, Figs. 105 9 and 17, which serve the two-fold purpose of holding the ends of the bag lengths away from the paste and facilitating the passage of said ends between the lower part of the belt 91 and the cylinder. 110

115 Located below the forward portion of the cylinder 48 is a transverse shaft 100, equipped with two miter gears 101 and also with two cams 102. Suitably supported above the said shaft 100 are miter gears 103, which are intermeshed with the gears 101; and extending through the said gears 103 so as to turn therewith and move up and down therein are shafts 104. These shafts 104 carry the sweeps 105 which 120 sweeps rotate inward, and in the direction of movement of the cylinder 48 and then outward in order to perform the function hereinbefore ascribed to them. The shafts 104 are raised by the cams 102 to put the 125 sweeps in proper position to serve the said purpose, and when the cams pass the lower ends of the shafts 104, the shafts and the sweeps 105 are depressed by the springs 106 which surround the shafts and are inter- 130

posed between the enlargements 107^a and 108^a fixed on the shafts. The said depression of the sweeps 105 is provided in order to enable the blades 74 and 75 and the carriages 73 to clear the said sweeps 105 incidental to the rotation of the cylinder. After passing and being operated on by the sweeps 105, the bags pass over a guide 107, Fig. 17—
 10 *i. e.*, between said guide and the cylinder; said guide serving to turn back the front wall of the forward open end of the bag. The bags then pass under a stripper 108 which is so denominated because its free
 15 end extends into the continuous groove 2 of the cylinder 48 and serves to assure the bags leaving the periphery of the cylinder and passing downward between the two upper finishing rolls 109. To prevent the bags
 20 from passing between the rolls 109 and then downward to the floor, we provide the finishing rolls 109 and a third finishing roll 110 with circumferential grooves 111, and we also provide wire guides 112, supported
 25 at 113 and curved over the adjacent roll 109 and in the grooves thereof and between the two rolls 109, and then between the other roll 109 and the roll 110 and in the grooves thereof. These guides assure the finished
 30 bags passing from the finishing rolls to the lower belt 114, and then upward and rearward between the opposed stretches of the belts 114 and 115 to the receptacle 116^a located within the machine with a view to
 35 economizing floor space which is an important advantage in paper bag factories. From the receptacle 116^a the finished bags are taken by an attendant of the machine. The belts 114 and 115 are carried by driven
 40 rollers 116 and idler rollers 117, Figs. 1 and 3.

It will be understood from the foregoing that the detailed operation ascribed to the group of features or organized mechanism carried by the cylinder 48 and shown in the central portion of Fig. 4, is common to the other five, similar groups of features or organized mechanisms carried by the cylinder 48.

45 Motion is transmitted from the shaft of the lower draw-roll 34 to the shaft of the fountain roller 42 by the gear train best shown in Figs. 15 and 16, which gear train is arranged adjacent the left-hand side of the machine, looking forward, and comprises a spur gear 118 fixed on the shaft of roll 34, a spur gear 119 intermeshed with the gear 118 and having an inner cam face 120, and a gear 121 fixed on the shaft of
 55 the fountain roller 42 and intermeshed with the gear 119. Extending loosely through the center of gear 119 is a fixed bracket 122, and fulcrumed on the said bracket is a lever 123. This lever carries anti-friction
 60 wheels 124 which are opposed to the cam

face of gear 119, whereby the lever is oscillated incidental to rotation of said gear. One arm of said lever 123 is disposed in a circumferentially grooved portion 125 of the shaft of fountain roll 42, and hence the said oscillation of the lever will be attended by reciprocation of the fountain roll 42 and the efficient distribution of ink therefrom on the inking roll 41. Aside from the features mentioned, the means for supplying ink to the form 40 may be of any type or construction consonant with the purpose of our invention.

The upper plate 29 is shown in Fig. 12 as provided with an opening 29^a, but this opening is immaterial, and may therefore be omitted without affecting our invention.

Particular reference will now be made to Figs. 18 to 22 of the drawings, and from the same it will be understood that the middle gripper 69 of each of the six organized mechanisms carried by the cylinder 48 is moved forward to grip a bag length by springs 126, and is moved rearward to release the bag length by the coöperation of an arm 127, fixed on the rock-shaft 128 of the gripper or formed integral with said rock-shaft 128, and a fixed cam 129 arranged within the cylinder and adjacent the left-hand side thereof, looking forward. In Fig. 21 the six grippers 69 and their arms 127 are shown as grouped about the fixed or stationary cam 129; the said arms 127 being provided with anti-friction wheels 130 to facilitate and render easy their movements around the cam. It will also be noted here that the springs 126 serve to press the grippers 69 forward when the positions of the arms 127 relative to the cam 129 permit, and that the coöperating 105 cam 129 and arms 127 operate at the proper time, see the bottom of Fig. 21, to move the grippers 69 rearward against the action of the springs 126 to release the bags.

The gripper 70—*i. e.*, the rear gripper 70, of each of the organized mechanisms carried by the cylinder 48, is provided with a rock-shaft 131, and fixed with respect to said rock-shaft is an arm 132, equipped with an anti-friction wheel 133. The six rear grippers 70 and their arms 132 are shown in Fig. 18, as grouped about the stationary cam 134 by which the rear grippers are opened or moved rearward to release the bags. The said rear grippers 70 are moved forward to grip the bags by springs 135 when the arrangement of the levers 132 relative to the stationary cam 134 permits. The grippers 68—*i. e.*, the forward grippers of the organized mechanisms are provided with rock-shafts 136, and fixed with respect to said rock-shafts are arms 137, equipped with anti-friction wheels 138. The six forward grippers 68 and their arms 137 are shown in Fig. 18, as grouped about the sta-

tionary cam 139, by which the forward grippers are opened or moved forward to release the bags. In Fig. 20, the stationary cam 129 is shown within the cylinder 48 at one side thereof, and the stationary cams 134 and 139 are shown inside the cylinder and at the opposite side thereof; the described operations of the grippers being accomplished by the rotation of the cylinder 48 about the said cams 129, 134 and 139. The rearward movement of the forward grippers 68 to grip bags is accomplished by springs 140, arranged in front of the grippers 68, with reference to the direction of rotation of the cylinder.

As best shown in Fig. 4, stationary cams 141 are located at opposite sides of the cylinder 48, and the in and out movements of the carriages 73 are accomplished incidental to the rotation of the cylinder 48 by reason of gudgeons 142 on the carriages 73 being disposed and movable in the circumferential grooves 143 of the said cams 141. The described movements of the gear sectors 82 incidental to the rotation of the cylinder 48 are accomplished by the coöperation of the lateral projections 83, with stationary cams 144; the said lateral projections 83 bearing on the perimeters of the said cams 144, Figs. 4 and 9. The described outward movements of the blades 74 radially—*i. e.*, away from the center of movement of the cylinder 48, are accomplished by the movements of the rods 78 over the projections 150 on the peripheries of the cams 141. One of the said projections 150 is clearly shown on one cam 141 in the upper portion of Fig. 17, and it will be understood in this connection that the projection 150 at the opposite side of the cylinder 48 is similarly located. We would also have it understood in this connection that the blades 74 are thin and resilient, and hence said blades will yield in passing outward from engagement with the bag lengths when the carriages 73 are moved outward.

The driving connections of the machine are best shown in Figs. 1 and 2, and by comparing said figures with the other figures, said driving connections will be readily understood. The primary driver of the machine is the transverse shaft 151, and this is equipped with the conventional loose and fast pulleys 152, Fig. 2, and 153, see dotted lines in Fig. 1. The said shaft 151 is also equipped with a balance wheel 154, see dotted lines in Fig. 1, and a cam 155. This latter operates on one arm of a vertically swinging lever 156 to oscillate the ironer and smoother 87, the other arm of the lever 156 being connected through a link 157 to a crank 158 on the transverse shaft 159 of the smoother and ironer 87. The smoother and ironer is swung rearward by the action of the cam 155 on the rear arm of lever 156,

and is swung forward by a tractile spring 160 interposed between and connected to the forward arm of the lever 156 and the main frame of the machine. On its rearward movement the smoother and ironer 87 serves to assist the lay back blades 75 in the first formation of the bottom. Said element 87 does this by smoothing the center of the rear wall of the bottom. It then moves forward to a position that enables the end of the bottom to strike it, and hence it retards the movement of said end for the purpose of assuring the end entering flat below the retainers 85. The plate 86, during the operation of the smoother and ironer 87, serves as a stationary back for the square formation of the rear wall comprised in the bottom during the manipulation of the paper to form the bottom.

Motion is transmitted from the shaft 151 to the shaft 165 of the cylinder 48 to drive the said cylinder through the medium of a spur gear 166 fixed on shaft 151, a spur gear 167 intermeshed with the gear 166, and a large spur gear 168 fixed on the shaft 165 and intermeshed with the gear 167. The shaft of the roll 49 is provided with a spur gear 170, which is intermeshed with the gear 168, and hence said roll 49 is rotated from said gear 168. The shaft of the roll 49 is also provided with a sprocket gear 171, and this latter is connected through a sprocket belt 173 with a sprocket gear 172 on the shaft 88, and hence said shaft 88 is also driven from the large gear 168. Fixed with respect to the combined pasting and tucking roll 99 is a spur gear 174, intermeshed with the large gear 168, and intermeshed with the said gear 174 is a gear 175 fixed with respect to the roll 98, and consequently it will be understood that said rolls 99 and 98 derive their motion from the large gear 168. The shaft 100 also derives its motion from the large gear 168, through the medium of a gear 180 intermeshed with the gear 168, and a gear 181 intermeshed with the gear 180 and fixed on the shaft 100. The shaft of the finishing roll 109 nearest the belts 114 and 115 is provided with a spur gear 182 which is intermeshed with a gear 183 on the shaft of the other roll 109, and said gear 183 is intermeshed with and driven by the large gear 168. The shaft of the lower finishing roll 110 is provided with a gear 184, which is intermeshed with the gear 182, and hence it follows that the finishing roll 110 will also be driven from the large gear 168. Motion is taken from the gear 166 on the primary drive-shaft 151 through gears 190, 191, 191^a and 192, to drive the rolls 116, and consequently the belts 114 and 115. The shaft of the rotary device 3 is driven from the gear 166 through the medium of the gear 167, a gear 195 fixed on the shaft 130

8

of the lower draw roll 34, a gear 196 intermeshed with the gear 195, and a gear 197 on said shaft of the rotary device 35. The lower draw roll is rotated through its said gear 195, and the upper draw roll 33 is rotated through its gear 198 which is intermeshed with the gear 195. The lower retarding roll 44 is provided with a gear 199, which is intermeshed with the gear 167, and the upper retarding roll 43 is provided with a gear 200, intermeshed with the gear 109, from which it follows that the rolls 43 and 44 will also be rotated from the gear 167.

15 201 is the belt through which the machine is driven from any suitable source of power, and our invention contemplates the provision of means peculiarly adapted to paper bag machines for shifting the said belt from 20 the fast pulley 153 to the loose pulley 152 in the event of it being necessary for any reason to suddenly stop the machine. The said means comprises a longitudinally disposed rock-shaft 202 arranged at the right-hand side of the machine, looking forward, and adjacent the floor. The said rock-shaft is provided with a bifurcated arm 203 which loosely receives the belt, and the shaft is further provided with a pedal lever 204.

25 30 The girl attendant of the machine stands at the right-hand side thereof, and inasmuch as it is the impulse of a girl to stamp down when startled or alarmed, it will be appreciated that the lever 204 provides a very 35 convenient means for enabling the girl attendant to shift the belt 201 to the loose pulley 152, and thereby quickly stop the machine. The said means also comprises an arm 205 fixed to and extending upward 40 from the rock-shaft 202, a rod 206 connected to the arm 205 and extending crosswise of the machine to the opposite side thereof and there provided with an angularly disposed arm 207, Figs. 1 and 24, and 45 a bell-crank lever 208 fulcrumed on a bracket 209 and having an upwardly extending arm connected to the rod 206 and also having a treadle 210 on its other arm. When anything out of the ordinary occurs 50 and startles the girl attendant of the machine she in following her natural impulse to stamp, depresses the lever 204, Fig. 2, and thereby shifts the belt and immediately stops the machine as is desirable.

55 55 The features shown in Figs. 1 and 24 are provided to enable the male attendant at the left-hand side of the machine, to quickly stop the machine and as quickly start the same. To stop the machine, the male attendant either presses the arm 207 inward with his knee, or else lifts the treadle 210 with his foot, the former being more convenient operation. It is the province and in fact is desirable for the male alone to

be able to start the machine, and the same 65 is accomplished either by the male attendant pressing downward on the treadle 210 or pulling outward on the arm 207; the former of course being the preferred mode.

70 By reference to Fig. 23, it will be understood that the roller 99 is provided with portions 210 for applying paste to the bottom portions of the bag lengths; and it will also be understood that there is a space 211 intermediate the tucking blades 99^a. The 75 tucking blades necessarily take some paste from the roller 98, and the said space 211 between the blades 99^a precludes paste getting upon the inside of the bag, which is an important advantage, inasmuch as paste applied to the inside of the bag would render the bag imperfect and unfit for use.

80 This completes the description of the preferred embodiment of our invention which has proved in actual practice to be a 85 smoothly operating machine possessed of large capacity and not liable to get out of order. In connection with the said embodiment, we desire it understood that irrespective of where springs are employed therein 90 other suitable means may be employed to serve the functions ascribed to the springs without departure from the scope of our claims; also, that in the future practice of the invention, such changes or modifications 95 may be made as fairly fall within the scope of our claims.

In Figs. 25 to 38 we show so much of a bag making machine as is necessary to impart an understanding of a modification of 100 our invention. The tube forming means of the modification may be of any approved construction, and therefore is not shown. The means for cutting bag lengths from said tube may also be of any suitable type, 105 though we prefer to employ for the purpose a striker or cutting-off device (not shown) located at the left of the mechanism in Fig. 25; said striker or cutting-off device being similar to the one disclosed in the Hirsch 110 and Eichberg Patent No. 903,570 of Nov. 10, 1908.

In Figs. 25 to 38; the directions of rotation of the rolling elements is indicated by small arrows, and the line of feed of the 115 paper tube is indicated by the large arrow *a*, Fig. 25.

Referring by letter and numeral to Figs. 25 to 38; *b* is a rotary cylinder section, provided with a tucking blade *c*. *d* is a 120 paste receptacle located in front of said section *b*; *e*, a roll for taking paste from said receptacle, and *f* a rotary paste-applying cylinder section. Below the cylinder section *f* is disposed the comparatively large 125 rolling cylinder *g* which corresponds to the rolling cylinder 48 of the preferred embodiment, and back of the cylinder *g* and under

the cylinder section *b* are two rolling cylinders *h* and *i*. The tubular bag length first passes in the direction of arrow *a* between the section *b* and the cylinder *h*, and by the 5 coöperation of an oscillatory clamp *j* on cylinder *h* with a spring *T*, Fig. 38, the bag length will be temporarily connected with and carried in the direction indicated by cylinder *h*. A stationary cam *k* moves the 10 clamp *j* to release. *l* is a stationary opener disposed in front of and adjacent the cylinder *h*, and *m m* are curved retainers which swing up and down and are raised as shown in Fig. 25 to enable the opener *l* to turn the 15 rear wall of the forward end of the bag length back when the length is tucked in the groove *n* of cylinder *h* and engaged and held by the oscillatory gripper *p*, which is moved to grip by the tractile spring *r*, and is 20 moved to release the bag at the proper time by the coöperation of the arm *s* on the rock-shaft of the gripper with a stationary cam *t*. Carried by the cylinder *h* and arranged 25 slightly in advance of the gripper *p* are oscillating blades *u* for engaging the inner portions of the side bellows in the tubular bag lengths. The said blades *u* are carried by levers *v*, and are moved inward by a tractile spring *w* and outward by stationary 30 cams *x*. It will also be observed by reference to Fig. 26, that the cylinder *h* is equipped with swinging or lay-back blades *y*, arranged in rear of the inwardly and outwardly movable blades *u*. The blades *y* are 35 carried by shafts *z* on the cylinder, and said shafts are equipped with pinions *a¹*. Said pinions are intermeshed with gear sectors *b¹* on arms *A* pivoted to the cylinder *h* at *B*. During the rotation of the cylinder *h* the 40 lay-back blades *y* are swung backward at the proper time by stationary cams *C* operating on anti-friction rolls carried by the arms *A*, and when the positions of the arms *A* to the stationary cams *C* permit, the 45 blades *y* are swung forward by springs *A²* to positions diametrically opposite those shown in Fig. 26. The shafts *z* and the blades *y* are moved inward and outward by the levers *D*, shown in Figs. 26 and 29. The 50 said levers are mounted to rotate with the cylinder *h*, and are pivoted at *E* to swing inward and outward, and are caused to oscillate by stationary cams *F* in circumferential grooves of which projections of the 55 levers are disposed.

The cylinder *h* is provided with one or more, preferably two, circumferential grooves *G*, and into said grooves extend strippers *H*, which, as their name imports, 60 are designed to assure the bag length leaving cylinder *h*, and passing to the periphery of the cylinder *i*. Connected to and depending from the strippers *H* is a guiding means *I* which extends around the lower portion

of the cylinder *i* and into grooves *J*, Fig. 27, 65 in the large cylinder *g*. The bag length passes from the cylinder *h* to the cylinder *i*, and from said cylinder *i* to the cylinder *g*, and while the length is interposed between the cylinders *i* and *g*, it is engaged at different times by tuckers *K* and *L* carried by the cylinder *i*; the tucker *K* being retracted by a flat spring *M*, Fig. 25, and the tucker *L* being retracted by tractile springs *N*, Fig. 70 75 32. At the proper time during the revolution of the cylinder *i*, the tuckers *K* and *L* are forced outward by the peripheral projection, on the stationary cam *P*, Figs. 25 and 30. It will also be seen by reference to Figs. 25, 28 and 32, that the cylinder *i* is 80 equipped at opposite sides with bag-engaging blades *Q*; said blades being disposed between said tuckers. The blades *Q* are carried by levers *R*, and the blades are moved outward by the coöperation of said levers 85 with stationary cams *S*. Each lever *R* is provided with trunnions journaled in a bracket at one side of the cylinder *i*, and the upper arm of each lever and the blade *Q* thereon are moved inward and yieldingly 90 held against outward movement by a torsion spring *T²*, Fig. 28. One of the cams *S* is shown in detail in Fig. 28. The comparatively large cylinder *g* is provided with 95 two organized mechanisms for gripping the bag lengths; the cylinder *g* being adapted as before stated to handle two lengths at one time. These organized mechanisms respectively comprise transverse grooves *1^x*, grippers *2^x* and *3^x* disposed in said grooves, 100 arms *4^x* fixed to the rock-shafts of the grippers, tractile springs *5^x* connected to said arms and the cylinder, and serving to move the grippers to grip, and stationary cams *6^x*, Figs. 25 and 27 which coöperate with the 105 arms *4^x* and serve at the proper times to move the grippers to release. It will also be observed that guiding means *7^x*, Fig. 25, 110 extends into the peripherally grooved portion of the cylinder *i* so as to assure a bag length leaving said cylinder and passing upward and forward with the cylinder *g*. By comparison of Figs. 25 and 27, it will be seen that sweeps *8^x* are provided to coöperate with the cylinder *g* for the same purpose 115 as the sweeps comprised in the preferred embodiment. The sweeps *8^x* are carried by shafts *9^x* equipped with beveled pinions *10^x*, and intermeshed with said pinions *10* are beveled gears *11^x*. Said sweeps *8^x* are rotated inward and forward in the same direction as the cylinder *g* to fold forward the rear wall of the opening at the forward end of a bag length. It will further be observed by reference to the right of Fig. 25 that 120 suitable guiding means is provided for conducting the bag lengths from the cylinder *g* to finishing means; said guiding means and 125

finishing means being of any suitable character consonant with the purpose of our invention.

In the practical operation of the modification, the movements of the parts are so timed that a bag length disposed between the cylinder section *b* and the cylinder *h* will first be engaged by the clamp *j* in the manner shown in Fig. 34, and then will be tucked in the groove *n* and engaged and held by the gripper *p*. Also, at the proper times the forward end of the length will be engaged by the blades *u* and *y* and the stationary opener *l*, and the forward end will be shaped and opened with the rear wall of the opening laid back on the cylinder. At the proper times the bag length after it passes under the opener *l*, will be released, and the length will then be delivered to the cylinder *i*. At the proper times when the length is between the cylinders *i* and *g*, the length will be engaged by the grippers 2 and 3 and carried around and forward on said cylinder *g*. During the movement of the bag length with the cylinder *g*, the sweeps 8^x will close or swing forward the rear wall of the forward end of the bag length, or in other words the rear wall of the bag bottom, and the guiding means before referred to, or rather the upwardly extending portion of said guiding means, will close the forward wall of the bag bottom, while the lower portion of the guiding means will assure the bag or bag length with its closed bottom leaving the cylinder *g*. While the bag length is on the cylinder *g* and *en route*, to a position between the sweeps 8^x, paste is applied to the bottom so that when the bag leaves the cylinder *g* it is completely constructed. It will be noted by reference to Fig. 25 that as one bag length is taken on the cylinder *g*, a completely constructed bag is leaving the cylinder, which of course contributes to the capacity of the modification.

While we have shown certain gearing for operating the working parts as described, we do not deem it necessary to enter into a detailed description of the said gearing, except to say that extraneous power is suitably applied to the shaft of the cylinder *h*, and is transmitted from the said shaft to the other working parts. It is also well to state in this connection that the cam shown in Fig. 26^a and in Fig. 26, and numbered 10^x, is fixed on the shaft 11^x of the rotary cylinder section *b*, and serves by co-operation with the toggle levers 12^x and the crank 13^x fixed on the upper shaft 14^x, to oscillate the gears 15^x on the latter shaft; the said gears 15^x being intermeshed with gear sectors 16^x, which are loose on the shaft 11^x and are fixed to the retainers *m*, which are also loose on the shaft. In this way during the

rotation of the shaft 11 the retainers *m* are 65 oscillated.

It will be gathered from the foregoing that there are several important features common to the preferred embodiment of our invention shown in Figs. 1 to 24, and the 70 modification shown in Figs. 25 to 38.

In the modification as in the preferred embodiment, wherever springs are employed other means may be substituted to serve the purposes ascribed to the springs, without 75 involving departure from the scope of our claimed invention.

Having described our invention, what we claim and desire to secure by Letters-Patent, is:

1. The combination of means for supporting a paper tube as the same is moved longitudinally, means for so moving the tube, and a rotary device mounted below the line of movement of the tube and provided with U-shaped cutting means for making thumb-hold cuts in the lower wall only of the tube at equidistant points in the length thereof; the said U-shaped cutting means being open at the rear, with reference to the direction of rotation of the rotary device whereby the making of the thumb-hold cuts is accompanied by the provision of tongues for use in the bottoming of the bags. 80

2. The combination of means for supporting a paper tube as the same is moved longitudinally, means for so moving the tube, and a rotary device for making thumb-hold cuts in the tube at equidistant points in the length thereof; said device comprising a 100 body, cutting means carried by the body, and resilient means for pressing the paper away from the cutting means subsequent to the production of a cut.

3. The combination of means for supporting a paper tube as the same is moved longitudinally, means for so moving the tube, and a rotary device for making thumb-hold cuts in the tube at equidistant points in the length thereof; said device comprising a 110 body, arched cutting means carried by the body, and spring fingers fixed to the body at points remote from the arched cutting means and having free ends arranged adjacent said means. 115

4. In a paper bag machine, the combination of a suitable support, means for supporting a tube of paper during the cutting of bag lengths therefrom, a roll mounted in the support, levers extending in the direction of the length of the roll and carried thereby and fulcrumed at intermediate points of their length to the roll in position to swing toward and from the center thereof; said levers having on their inner arms blades for making shear cuts, and means adapted to engage the outer arms of the levers incidental to the rotation of the roll 120 125

and thereby cause depression of the inner arms of the levers and the blades carried thereby.

5. In a paper bag machine, the combination of a suitable support, a roll mounted therein, means for supporting a tube of paper during the cutting of bag lengths therefrom, levers extending in the direction of the length of the roll and carried thereby and fulcrumed at intermediate points of their length to the roll in position to swing toward and from the center thereof; said levers having on their inner arms toothed blades for making shear cuts and having on their outer arms anti-friction rollers, tappets adapted incidental to the rotation of the roll to engage said anti-friction rollers and thereby depress the blade-bearing arms of the levers, and means for restoring the levers to their normal position when they pass out of engagement with the tappets.

6. In a paper bag machine, the combination of a suitable support, means for supporting a tube of paper during the cutting of bag lengths therefrom, a roll mounted in the support, a lever extending in the direction of the length of the roll and carried thereby and fulcrumed at an intermediate point of its length to the roll in position to swing toward and from the center thereof; said lever having on its inner arm a blade for making a shear cut, and means adapted to engage the outer arm of the lever incidental to the rotation of the roll and thereby cause depression of the inner blade-bearing arm of the lever.

7. In a paper bag machine, the combination of a suitable support, means for supporting a tube of paper during the cutting of bag lengths therefrom, a roll mounted in the support, a lever extending in the direction of the length of the roll and carried thereby and fulcrumed at an intermediate point of its length to the roll in position to swing toward and from the center thereof; said lever carrying on its inner arm a toothed blade and carrying on its outer arm an anti-friction roller, means for engaging the anti-friction roller incidental to rotation of the roll and thereby depressing the blade-bearing arm of the lever, and means for restoring the lever in its normal position and maintaining the lever in such position except when it is rocked by the means engaging the anti-friction roller.

8. In a paper bag machine, the combination of a suitable support, means for supporting a tube of paper during the cutting of bag lengths therefrom, a roll mounted in the support, a lever extending in the direction of the length of the roll and carried thereby in position to swing toward and from the center thereof and provided with

cutting-off means, and means for oscillating 65 said lever incidental to rotation of the roll.

9. A machine for making paper bags of the self-standing square type, comprising means for forming a strip or web of paper into a tube, means for feeding the said tube forward, a rolling cylinder to which the tube is fed, means coöperating with said cylinder to cut bag lengths from the tube, means for causing a slackening or buckling of the tube precedent to the said cutting-off operation, 75 means for forming the bottoms of the bags while the bag lengths are on the cylinder, means for pasting the bag bottoms while the bag lengths are on the cylinder, means for turning said bottoms while the bag lengths 80 are on the cylinder, and means for completing the bottoms while the bag lengths are on the cylinder and before the bags leave the same.

10. A machine for making paper bags of the self-standing square type, comprising means for forming a strip or web of paper into a tube, means for feeding the said tube forward, a rolling cylinder to which the tube is fed, means coöperating with said cylinder to cut bag lengths from the tube, means for causing a slackening or buckling of the tube precedent to the said cutting-off operation, means for forming the bottoms of the bags while the bag lengths are on the cylinder, means for turning said bottoms while the bag lengths are on the cylinder, means for applying paste or pasting the bag bottoms precedent to the turning of said bottoms, means for completing the bottoms 100 while the bag lengths are on the cylinder and before the bags leave the same, means for taking the bags with completed bottoms from the cylinder, means for pressing the bags so taken, a receptacle located within the machine as contra-distinguished from a receptacle without the same, and means for receiving bags from the pressing means and delivering the same to the receptacle, all in 110 continuous operation.

11. A machine for making paper bags, comprising means for forming a strip or web of paper into a tube, means for feeding the said tube forward, a rolling cylinder to which the tube is fed, means coöperating with said cylinder to cut bag lengths from the tube, means for causing a slackening or buckling of the tube precedent to the said cutting-off operation, means for forming the bottoms of the bags while the bag lengths are on the cylinder, means for pasting the bag bottoms while the bag lengths are on the cylinder, means for turning said bottoms while the bag lengths are on the cylinder, and means for completing the bottoms while the bag lengths are on the cylinder and before the bags leave the same.

12. A machine for making paper bags,

- comprising means for forming a strip or web of paper into a tube, means for feeding the said tube forward, a rolling cylinder to which the tube is fed, means coöperating with said cylinder to cut bag lengths from the tube, means for causing a slackening or buckling of the tube precedent to the said cutting-off operation, means for forming the bottoms of the bags while the bag lengths are on the cylinder, means for turning said bottoms while the bag lengths are on the cylinder, means for applying paste to the bag bottoms precedent to the turning of said bottoms, means for completing the bottoms while the bag lengths are on the cylinder and before the bags leave the same, means for taking the bags with completed bottoms from the cylinder, means for pressing the bags so taken, a receptacle located within the machine as contra-distinguished from a receptacle without the same, and means for receiving bags from the pressing means and delivering the same to the receptacle, all in one continuous operation.
13. A machine for making paper bags, comprising means for forming a strip or web of paper into a tube, means for feeding the said tube forward, a rolling cylinder to which the tube is fed, means coöperating with said cylinder to cut bag lengths from the tube, means for causing a slackening or buckling of the tube precedent to the said cutting-off operation, means for forming the bottoms of the bags while the bag lengths are on the cylinder, means for applying paste to the bottoms so formed, means for turning said bottoms while the bag lengths are on the cylinder, means for completing the bottoms while the bag lengths are on the cylinder, pressing rolls, means for taking the bags with completed bottoms from the cylinder and assuring the passage of the same between said rolls, a receptacle located within the machine, and driven belts having opposed stretches adapted to receive between them bags from the pressing rolls and deliver said bags to the receptacle.
14. A paper bag machine comprising the following instrumentalities in combination, to wit:—a rolling cylinder, means for feeding a tube of paper thereto, means coöperating with said cylinder to cut bag lengths from the tube, means for forming the bottoms of the bags while the bag lengths are on the cylinder, means for applying paste to the bag bottoms while the bag lengths are on the cylinder, means for turning said bottoms while the bag lengths are on the cylinder, and means for completing the bottoms while the bag lengths are on the cylinder; the said means operating in the order named on each bag length and at different points about the cylinder.
15. A paper bag machine comprising the following instrumentalities in combination, to wit:—a rolling cylinder, means for feeding a tube of paper thereto, means for causing a longitudinal buckling or slackening of the portion of the tube immediately adjacent the cylinder, means coöperating with said cylinder to cut bag lengths from the tube, means for forming the bottoms of the bags while the bag lengths are on the cylinder, means for applying paste to the bag bottoms while the bag lengths are on the cylinder, means for turning said bottoms while the bag lengths are on the cylinder, and means for completing the bottoms while the bag lengths are on the cylinder; the said means operating in the order named on each bag length and at different points about the cylinder.
16. A paper bag machine comprising the following instrumentalities in combination, to wit:—a rolling cylinder, means for feeding a tube of paper thereto, groups of means arranged at intervals on the cylinder for taking hold of and releasing bag lengths at the proper times, means coöperating with the cylinder to cut bag lengths from the tube, means for coöperating with the cylinder for forming the bottoms of the bags while the bag lengths are on the cylinder, means for applying paste to the bag bottoms while the bag lengths are on the cylinder, means for turning said bottoms while the bag lengths are on the cylinder, and means for completing the bottoms while the bag lengths are on the cylinder; the said means operating in the order named on each bag length and at different points about the cylinder.
17. A paper bag machine comprising the following instrumentalities in combination, to wit:—a rolling cylinder, means for feeding a tube of paper thereto, means for causing a longitudinal buckling or slackening of the tube of paper immediately adjacent the cylinder, groups of means arranged at intervals on the cylinder for taking hold of and releasing bag lengths at the proper times, means coöperating with the cylinder to cut bag lengths from the tube buckled as stated, means for coöperating with the cylinder for forming the bottoms of the bags while the bag lengths are on the cylinder, means for applying paste to the bag bottoms while the bag lengths are on the cylinder, means for turning said bottoms while the bag lengths are on the cylinder, and means for completing the bottoms while the bag lengths are on the cylinder; the said means operating in the order named on each bag length and at different points about the cylinder.
18. In a paper bag machine, the combination of a rolling cylinder having at its opposite sides outwardly extending or lateral pairs of guide rods, means carried by said

cylinder for taking hold of a bag length having longitudinal tucks or bellows in its sides, carriages supported at opposite sides of the cylinder on said rods and movable 5 circularly with the cylinder and also movable with respect to the cylinder and toward and from the longitudinal vertical center thereof, cams for so moving the carriages with respect to the cylinder incidental to rotation of the cylinder, a blade carried by each carriage and mounted to swing and spring radially, *i. e.*, away from and toward the center of the cylinder and with respect to both carriage and cylinder; said blade 10 being resilient, means for moving the blades in a direction away from the center of the cylinder incidental to rotation of the cylinder, a vertically swinging blade also carried by each carriage and movable from a position on the first-named blade backward, with reference to the direction of movement of the cylinder, to a point about diametrically opposite the first-named blade, and means for swinging the second-named blades 15 incidental to the rotation of the cylinder.

19. In a paper bag machine, the combination of a rolling cylinder having at its opposite sides outwardly extending or lateral pairs of guide rods, means carried by said cylinder for taking hold of a bag length having longitudinal tucks or bellows in its sides, carriages supported at opposite sides of the cylinder on said rods and movable in a circular direction with the cylinder and 20 also movable synchronously inward and synchronously outward with respect to the cylinder, cams for so moving the carriages inward and outward, a blade carried by each carriage and movable radially; said blade 25 being resilient and having a foot extending inward toward a line extending through the center of the cylinder, cams for coöperating with said feet and moving the blades outward incidental to rotation of the cylinder and then releasing the blades, a vertically swinging blade carried by each carriage and movable from a position on the first-named blade backward, with reference to the direction of movement of the 30 cylinder, to a point about diametrically opposite the first-named blade, cams and means intermediate said cams and the second-named blades for swinging the latter incidental to the rotation of the cylinder.

55 20. In a paper bag machine, the combination of a rolling cylinder having at intervals groups of working parts and appurtenances, each group comprising a forward gripper, a middle gripper and a rear gripper; said cylinder also having a continuous circumferential groove intersecting the said grippers and the abutments opposed thereto, carriages supported at opposite sides of the cylinder and movable in a

circular direction with the cylinder and 65 also movable synchronously inward and synchronously outward with respect to the cylinder, a blade carried by each carriage and movable radially; said blade being resilient, a vertically swinging blade carried by 70 each carriage and movable from a position on the first-named blade backward, with reference to the direction of movement of the cylinder, and means for actuating the grippers, means for moving the first-named 75 blades radially outward, means for swinging the second-named blades, and means for moving the carriages inward and outward incidental to the rotation of the cylinder.

21. The combination of a rotary cylinder 80 having pairs of lateral guide rods at opposite sides thereof, carriages movable outward and inward on said supports, means for so moving the carriages incidental to rotation of the cylinder, blades carried by the 85 carriages and movable radially, said blades being resilient and being therefore adapted of themselves to move inward, means for moving the said blades radially outward incidental to rotation of the cylinder, blades 90 mounted on the carriages to swing vertically from positions on the first-named blades to opposite positions, means for moving the second-named blades in one direction incidental to rotation of the cylinder, and means 95 for moving the second-named blades in the opposite direction.

22. The combination of a rotary cylinder, a carriage supported and movable laterally inward and outward at one side of said cylinder, means for so moving the carriage incidental to rotation of the cylinder, a radially movable blade on the carriage, said blade being resilient and being therefore adapted of itself to move radially inward, means for 100 removing said blade radially outward incidental to rotation of the cylinder, a blade mounted on the carriage to swing vertically, means for swinging said blade in one direction incidental to rotation of the cylinder, 110 and means for swinging the blade in the opposite direction.

23. The combination of a rotary cylinder, a carriage supported and movable outward and inward at one side of the cylinder, 115 means for so moving the carriage during rotation of the cylinder, a rock shaft journaled on the carriage and equipped with a pinion, a blade fixed to the inner portion of and adapted to turn or swing with the shaft, 120 the said blade projecting from the shaft and toward the longitudinal vertical center of the cylinder, and being therefore adapted to enter the side fold of a tucked tube, a lever mounted on the carriage and having a gear 125 intermeshed with said pinion, and means for actuating said lever during rotation of the cylinder.

24. The combination of a rotary cylinder, a carriage supported and movable outward and inward at one side of the cylinder, means for so moving the carriage during 5 rotation of the cylinder, a radially movable blade mounted on the carriage, means for moving the blade radially outward during rotation of the cylinder, said blade being resilient and being therefore adapted to 10 move radially inward of itself.

25. The combination of a rotary cylinder, a carriage supported and movable outward and inward at one side thereof, a blade mounted on the carriage to move radially, 15 said blade being resilient and therefore movable of itself inward, means for moving said blade outward incidental to rotation of the cylinder, a shaft journaled on the carriage and provided with a pinion, a blade carried 20 by said shaft and fixed thereto and extending from the shaft inward toward the longitudinal vertical center of the cylinder whereby it is adapted to enter the side fold of a tucked tube, a lever mounted on the 25 carriage and having on one arm a gear sector intermeshed with the pinion, means for rocking said lever in one direction incidental to rotation of the cylinder, and means for rocking the lever in the opposite direction. 30

26. The combination of a rotary cylinder having a circumferential groove, four transverse grooves spaced apart and communicating with said groove, notched grippers arranged one in each of the three rear 35 grooves, means for causing the forward gripper to grip rearward and the intermediate and rear gripper to grip forward incidental to rotation of the cylinder, carriages mounted on the cylinder at opposite 40 sides thereof and movable inward and outward, means for so moving the carriages incidental to rotation of the cylinder, radially movable blades mounted on the carriage, means for moving said blades in one direction, 45 during rotation of the cylinder, means for moving said blade in the opposite direction, vertically swinging blades also mounted on the carriage, means for swinging said blades in one direction during rotation of 50 the cylinder, means for swinging said blades in the opposite direction, a roll mounted adjacent the cylinder and provided with a tucking blade and cutting-off means, a paste-applying roll mounted adjacent the cylinder 55 and provided with spaced tucking blades, an oscillatory smoother or ironer arranged in front of the first-named roll, a wheel mounted in front of the smoother and ironer and provided with opening means, a belt passed 60 around said wheel and an idler disposed below the same and having a stretch opposite to the cylinder, retaining means arranged adjacent the periphery of the cylinder, ro-

tary sweeps movable up and down to clear the carriages, etc., of the cylinder, and means extending into the circumferential groove of the cylinder for taking bags therefrom. 65

27. In a paper bag machine, the combination with a rolling cylinder provided with grooves, means carried by the cylinder for gripping bag lengths in said grooves of the cylinder, and a roller opposed to the perimeter of the cylinder and provided with paste-applying means and with a peripherally projecting tucking blade and also provided with other peripherally projecting tucking blades arranged in alinement with each other and separated by an intervening space, for the purpose set forth. 70 75

28. In a paper bag machine, the combination of a rolling cylinder, bag grippers carried by said cylinder, means for operating said grippers incidental to rotation of the cylinder, radially movable blades and lay-back blades carried by and arranged at opposite sides of the cylinder, means for operating said blades incidental to rotation of the cylinder, means for cutting bag lengths from a tube and on the cylinder, a stationary plate disposed in front of said cutting means, a smoother or ironer that oscillates in front of said plate, a rotary opener disposed in front of said ironer or smoother, means for applying paste to bag lengths on the cylinder and arranged in front of said opener, with reference to the direction of rotation of the cylinder, means for folding forward the back wall of the bag bottom on the cylinder; said means being arranged in advance of the paste-applying means, and means arranged in advance of the forward folding means, with reference to the direction of rotation of the cylinder for folding back the front wall of the bag bottom on the 90 back wall. 95

29. In a paper bag machine, the combination of a rolling cylinder, bag grippers carried by said cylinder, means for operating said grippers incidental to rotation of the cylinder, radially movable blades and lay-back blades carried by and arranged at opposite sides of the cylinder, means for operating said blades incidental to rotation of the cylinder, means for cutting bag lengths from a tube and on the cylinder, a stationary plate disposed in front of said cutting means, an oscillatory smoother or ironer in front of said plate, a rotary opener in front of said ironer or smoother, a belt actuatable by the opener and having a stretch opposed to the perimeter of the cylinder, curvilinear retainers opposite the perimeter of the cylinder, means for applying paste to bag lengths on the cylinder and arranged below said 110 115 120 125 belt, guard means above the paste-applying

means, means for folding forward the back wall of the bag bottom on the cylinder; said means being arranged in advance of the paste-applying means, and means arranged 5 in advance of the forward folding means, with reference to the direction of rotation of the cylinder, for folding back the front wall of the bag bottom on the back wall.

30. In a paper bag machine, the combination of a rolling cylinder having at intervals groups of working parts and appurtenances, each group comprising a forward gripper, a middle gripper and a rear gripper; said cylinder also having a continuous 10 circumferential groove intersecting the said grooves and the abutments opposed thereto, carriages supported at opposite sides of the cylinder and movable in a circular direction with the cylinder and also movable synchronously inward and synchronously outward with respect to the cylinder, a blade carried by each carriage, and movable radially; said blade being resilient, a vertically swinging blade carried by each carriage and movable from a position on the first-named blade backward, with reference to the direction of movement of the cylinder, and means for actuating the grippers, means for moving the first-named blades radially outward, means for swinging the second-named blades, means for moving the carriages inward and outward incidental to the rotation of the cylinder, means for cutting on the cylinder lengths from a paper 25 tube, a stationary backing plate disposed in front of the cutting means, an oscillatory smoother or ironer disposed in front of said plate, a rotary opener mounted in front of the smoother or ironer, means for applying paste to the bag lengths on the cylinder, and means for closing the walls of the openings at the forward ends of the bag lengths.

31. In a paper bag machine, the combination of a rotating cylinder, a set of three bag grippers carried thereby; the forward gripper of said set gripping rearward and the two rear grippers gripping forward, and means for actuating the said grippers incidental to the rotation of the cylinder so 30 that the middle gripper takes hold of a bag length first, the forward gripper takes hold of a bag length second, and the rear gripper takes hold of a bag length third and also so that the rear gripper releases the bag length first, the front gripper releases the bag length second and the middle gripper releases the bag length third, for the purpose set forth.

32. In a paper bag machine, the combination of a rolling cylinder, bag gripping means carried thereby, means for moving the gripping means in one direction, means for moving the gripping means in the op-

posite direction incidental to rotation of the cylinder, rotary sweeps for closing the rear 65 wall of a bag bottom on the cylinder, said sweeps being mounted to rotate inward and in the direction of movement of the cylinder and then outward and means for closing the front wall of the bottom on the rear 70 wall while on the cylinder.

33. In a paper bag machine, means for forming a strip or web of paper into a tube having side tucks or bellows, comprising a hanger, a longitudinal plate connected with the hanger and having an upwardly disposed rear end, means over which the strip of paper is guided in its forward movement; said means being located in rear of and in a plane above that of the said upwardly-disposed end of the plate, means for applying paste longitudinally to the paper as it passes over the guiding means, a second longitudinal plate arranged above and spaced from said first-named plate, side 85 plates having their inner edge portions spaced apart and arranged between and spaced from the first and second-named plates, upright spaced bars rising at opposite sides of the lower longitudinal plate 90 adjacent the hanger and suitably supported and having convex opposed sides, and means for pressing the upper edge portion of the strip or web against the other edge portion thereof. 95

34. In a paper bag machine, the combination of a frame, a rolling cylinder mounted in the frame and having transverse grooves, swinging grippers actuatable in said grooves, means for actuating the grippers incidental to rotation of the cylinder, shafts mounted in the frame and disposed at opposite sides of the cylinder, sweeps mounted on the upper portions of said shafts, said sweeps being arranged to operate upon a partially 100 formed blank while it is held by the grippers, and means for rotating said sweeps. 105

35. In a paper bag machine, the combination of a frame, a rolling cylinder mounted in the frame and having transverse 110 grooves, swinging grippers actuatable in said grooves, means for actuating the grippers incidental to rotation of the cylinder, shafts mounted in the frame and disposed at opposite sides of the cylinder, sweeps mounted 115 on the upper portions of said shafts, said sweeps being arranged to operate upon a partially formed blank while it is held by the grippers, miter gears mounted on said shafts, miter gears intermeshed with those 120 on the shafts, and means for rotating the latter gears in a direction to swing the sweeps inward and forward.

36. In a paper bag machine, the combination of a cylinder, bag-engaging blades 125 disposed at opposite sides of the cylinder,

levers carrying the said blades and carried in turn by the cylinder, means for actuating said levers incidental to rotation of the cylinder, lay-back blades disposed in rear of 5 the first-named blades, shafts carried by the cylinder and disposed at opposite sides thereof and carrying the lay-back blades, pinions fixed on said shafts, levers carried by the cylinder and having gear segments 10 intermeshed with said pinions, means for moving said levers in one direction inci-

dental to rotation of the cylinder, and means for moving the levers in the opposite direction incidental to rotation of the cylinder.

In testimony whereof we have hereunto 15 set our hands in presence of two subscribing witnesses.
